UNITED STATES PATENT OFFICE.

SVEND PETERSEN, OF DETROIT, MICHIGAN.

TOY.

Application filed May 7, 1924. Serial No. 711,544.

To all whom it may concern:

Be it known that I, SVEND PETERSEN, a subject of the King of Denmark, whose residence and post-office address is 4708 Commonwealth Avenue, Detroit, county of Wayne, and State of Michigan, have invented certain new and useful Improvements in Toys, of which the following is a specification.

10 This invention relates to new and useful improvements in toys, and has for its object to provide a plaything, which will prove of interest and intellectual benefit to children and which may be manufactured at a very

15 small cost.

With the above and other objects in view, the invention consists of the novel features of construction, combination and arrangements of parts hereinafter fully described 20 and claimed and illustrated in the accompanying drawings forming part of this specification, in which similar characters of reference indicate corresponding parts in all views, and in which—

25 Figure 1 is a perspective view of a tube enclosing a piece of toy, said tube forming part of same.

Figure 2 is a transverse section on line A—A of Fig. 1; Fig. 3 is a perspective view 30 of an inner tube inserted in Fig. 1 and upon which the spring is coiled; Fig. 4 is a perspective view of a parachute; Fig. 5 is a detail perspective view of the top plate of said parachute, with the covering removed; 35 Fig. 6 is a detail view of the spring compressing bar with the seat attached.

Referring in detail to the drawings 10 designates a cylindrical tube, made of pasteboard, and having a flat closed bottom and 40 an open top, which top when the device is not in use, may be closed by a cover 11, said cover having flanges fitting snugly to said tube, and may be loosely secured to same by a string 20. The tube 10 has on each side 45 longitudinal recesses, diametrically disposed, as shown at 12; said recesses have at their lower end enlarged portions to form a stop notch 13. A trigger or lever 14 is pivotally secured by a tag to said tube on each side of 50 said notch. In Fig. 3 is shown an inner tube 15, preferably made of thin sheet metal, and which has its lower end resting at the bottom of tube 10; said inner tube has longitudinal recesses 12^a symmetrical with those

indicated at 12. The tube 15 is considerably 55 shorter than tube 10 as indicated at 16 and has a considerably less width thereby giving space for a coiled spring 17 which is wound around said inner tube. This spring is kept in place by a spring compressing bar 18, 60 which has its ends projecting from said tube 10 through recesses 12 and which has an annular seat 19 fastened thereon by means of screws 21. This seat is made of hard rubber, but may be made of any suitable material; it is provided with a central opening 22 and is adapted to slide down inside the inner tube when the spring by means of the bar 18 is compressed.

65 A parachute shown in Fig. 4 comprises an annular top plate 23, preferably made of hard rubber, said top plate has perforations adjacent to the edge thereof, said perforations being arranged in circular order as indicated at 24. To this top plate is fastened 70 loosely by way of said perforations, thin wires 25 of equal length, which wires have their ends twisted upon themselves thereby forming a loop at each end; the upper loop 75 attaches the wire to said top plate as indicated at 24, while the lower loops 26 are connected to elastic strings 27. These elastic strings, all of the same length, are with their free ends fastened to an annular base-seat, 80 or gondola, 28, preferably made of rubber 85 and having a central opening as indicated at 29.

The parachute is covered with a thin fabric 30, which fabric is fastened by a few 90 stitches of thread to the top plate and wire-ribs. On the base-seat 28 is placed a small doll 31 made of rubber or any suitable material. When the parachute, which according to above description is very collapsible, 95 is folded together it may be placed in the upper part of tube 10; the base-seat 28 being of the same dimensions as the seat 19 will then rest on this, and sink somewhat into said inner tube 10 when the spring 17 is compressed.

100 By force of the fingers applied to the bar 18 the spring 17 may be compressed to an extent that the projecting ends of the bar may be pushed into the notch 13. By pulling the trigger 14 the spring compressing bar 18 will be released, causing the spring 105 to expand and the impetus imparted thereby through the seat 19 to the base-seat of the

parachute will throw this a considerable distance up in the air. Falling down the weight of the doll and the base-seat 28 will cause the parachute to unfold quickly, 5 whereafter it will descend slowly.

While I have shown and described the preferred construction and arrangement of the various elements, it will be understood that the invention is susceptible to a great 10 many minor modifications without departing from the essential feature or sacrificing any of the advantages thereof.

Having thus described the invention what is claimed is:

15 1. A device of the character described, in combination, a double tube, a coiled spring inserted between said tubes, means for compressing said coiled spring, and a gondola attached to a parachute, said gondola and 20 parachute, when collapsed, being adapted to

slide loosely into the upper part of said tubes, as specified.

2. A device of the character described comprising an outer-tube, or case, having an inner tube essentially cylindrical in shape, 25 both with longitudinal recesses elongated into stop notches at their lower end, a spring compressing bar with a seat attached thereto, a spring releasing lever pivotally secured to said outer tube, and a parachute, said parachute having a cover of thin fabric, a top plate with perforations, wires loosely connected thereto, elastic strings having one end connected to said wires and the other end to a gondola or base-seat, substantially as 30 shown and described.

In testimony whereof, I have hereunto set my hand,

SVEND PETERSEN.
